CLAIM

The ornamental design for a water tank base, as shown and described.

DESCRIPTION

FIG. 1 is an isometric view of a water tank base showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof; and,

FIG. 7 is a bottom view thereof

The broken lines shown in the figure drawings depict portions of the water tank base which form no part of the claimed design.

1 Claim, 6 Drawing Sheets# US D901,769 S
